UNITED STATES PATENT OFFICE.

GEORGE E. FULLER, OF CHICAGO, ILLINOIS.

DESIGN FOR A SIGN.

49,510.

Specification for Design. Patented Aug. 15, 1916.

Application filed June 19, 1916. Serial No. 104,620. Term of patent 7 years.

To all whom it may concern:

Be it known that I, GEORGE E. FULLER, a citizen of the United States, residing at Chicago, in the county of Cook and State of Illinois, have invented a new, original, and ornamental Design for Signs, of which the following is a specification, reference being had to the accompanying drawing, forming part thereof.

The figure is a perspective view of a sign, showing my new design.

I claim:

The ornamental design for a sign, as shown.

GEO. E. FULLER.

Witnesses:

LEWIS T. GREIST,
MILTON Y. MILLER.
